UNITED STATES PATENT OFFICE.

TERRILL WILLIAM McCORMICK, OF DENTON, TEXAS.

SQUARE.

981,867.

Specification of Letters Patent. Patented Jan. 17, 1911.

Application filed February 15, 1910. Serial No. 543,975.

To all whom it may concern:

Be it known that I, TERRILL W. McCORMICK, citizen of the United States, residing at Denton, in the county of Denton and 5 State of Texas, have invented certain new and useful Improvements in Squares, of which the following is a specification.

My invention relates to a bevel provided with tables whereby, when the width of a 10 building is known and the rise per foot of the rafters is given, the length of the rafters and the angle at which the ends of said rafters are to be cut, may be readily ascertained.

15 An important object of my invention is to provide a bevel, so constructed that only one adjustment of the same is required to cut both ends of a rafter.

The final object of my invention is to provide a device of the above character, which 20 will be simple in construction, easy to operate, and which will save time in the cutting of rafters.

My invention consists generally of a triangle square, to which is movably secured a 25 ruler.

In the accompanying drawings, forming a part of this specification, and in which like numerals are employed to designate like 30 parts throughout the same, Figure 1 is a side view of the bevel. Fig. 2 is a similar view of the opposite side of the bevel, parts thereof being broken away. Fig. 3 is an end view of the same. Fig. 4 is a side view 35 of the ruler removed.

In the preferred embodiment of my invention as illustrated in the drawings, 1 designates a triangle square, comprising sides 2 and 3, which join each other and are 40 at right angles to each other. The sides 2 and 3 are connected near their free ends by a section of material 4, forming a plate for tables, to be hereinafter described. I preferably form the triangle square 1 of sheet 45 metal, such as steel, and upon one side of the plate 4, is formed a table 5, which I term the "hip and valley table" for it is the table to be used in calculating the length of the hip and valley rafters. Upon the opposite side of the plate 4 is arranged a table 6, 50 which I term "the main rafter table", since the same is employed in cutting the main rafters. The tables 5 and 6 may be formed upon the plate 4 by any suitable means, or 55 the same may be stamped upon the same.

I further provide a ruler comprising spaced sides 7, which are connected at their ends by sections of material 8. The ruler is arranged upon the apex of the triangle square 1, as shown in Fig. 1, the sides 7 of the ruler being arranged upon opposite sides of the square 1. A thumb screw 9 passes through the ruler and the square 1, whereby said ruler may be clamped to the square at a desired angle. Near one end of the ruler, is a ruler-blade 10 which is disposed between the sides 7 of the ruler and pivotally connected thereto, by means of a thumb screw 12. The ruler-blade 10 may thus be adjusted at a desired angle to the sides 7 of the ruler, 60 and clamped thereto, in such position. The ruler-blade 10 may preferably be formed of sheet metal and the ruler comprising the sides 7 may preferably be formed of hard wood. Adjacent the middle of the sides 7 of the ruler, the triangle square 1 is provided upon its opposite sides with a plurality of radially extending lines 16, which intersect each other at a common point 17. The lines 16 are designated respectively by 65 figures 5" to 15", inclusive, which correspond to figures 5" to 15" inclusive of a vertical row of figures 15 of the table 6, for a purpose to be hereinafter explained. Upon the same side of the square 1, with the table 6, 70 is arranged a jack table 15^a comprising vertical and horizontal rows of figures. The left hand vertical row of figures indicates the rise per foot of the jack rafters and the top horizontal row of figures indicates the 75 distance of the jack rafters apart. 80

In the use of the device, when cutting main rafters, I employ the main rafter table 6. In order that this table may not become mixed in the mind of the user with table 5, 90 I distinguish the same by the use of the words "Length of main rafters", which is placed near the left hand end of the table, as at 13, and shows that the table 6 is to be employed in ascertaining the length of main 95 rafters. The table 6 is formed of horizontal and vertical rows of figures, and the top horizontal row 14, running from 2 feet to 100 20 feet is used to designate one half of the width of the building for which rafters are to be cut. Near the right hand end of the table 6 is a vertical row of figures 15, which 105 form a part of the table 6, and run from 5" to 15", inclusive. This row of figures 15 is employed to designate the rise per foot 110

of the rafters, and the figures of the row 15 are arranged in horizontal alinement with corresponding rows of horizontal figures in the table 6. Suppose that it is desired to 5 cut main rafters for a building which is 30 feet wide, the operator follows the figures in the top horizontal row until he comes to 15'. If it is desired that the rafters should rise 7 inches per foot, the operator goes 10 down the column 15 until he locates 7", and then by following the adjacent corresponding horizontal row of figures, he locates a group of figures which lies directly under the 15' of the top horizontal row. This 15 group of figures is 17' 4 $\frac{1}{4}$ " and indicates that the rafters must be cut 17 feet and 4 $\frac{1}{4}$ inches long. Further, if the rafters are to have a rise of 7 in. per foot of length, their lower and upper ends may be marked for 20 cutting, by loosening the thumb screw 9 and setting the lower edge of the ruler upon the line 7' of the lines 16. The ruler is then clamped to the square 1 and the bottom and top of the rafter may be marked by ruling 25 respectively upon the sides of the square marked "Bottom cut" and "Top cut". It is thus seen that both ends of the rafter are marked for cutting by a single adjustment of my device, thus saving a great deal of 30 time and work.

The hip and valley table 5, is formed of horizontal and vertical rows of figures and the top horizontal row of figures indicate one half of the width of the building. At 35 the left hand end of the table 5 is arranged a vertical row of figures 18 indicating the rise per foot of the hip and valley rafters. In a similar manner to the main rafters, the length and angle at which the ends of 40 the hip and valley rafters are to be cut may be readily ascertained from the table 5, when the width of the building and rise per foot of the hip and valley rafters are given.

In cutting jack rafters the ends of the 45 same are first marked as for cutting main rafters, and the upper end of the jack rafter is further marked for cutting so that the same will fit against a hip rafter. The second marking of the upper end of the jack 50 rafter is accomplished in the following manner: If the roof rises 8 inches per foot, the ruler blade 10 is set so that the line 8" coincides with the upper edge of sides 7 of the

main ruler and said ruler blade is then clamped in such position. The jack rafter 55 is then marked upon its upper and lower sides by ruling along the edge of the ruler blade 10. Jack rafters decrease in length as they are arranged farther away from the main rafter, and the length of a jack rafter 60 may be readily ascertained by reference to the jack rafter table 15^a, illustrated in Fig. 1. If the roof rises 8 in. per foot and the jack rafter next to the main rafter is placed 16" from the main rafter, then by going 65 down the vertical row of figures below 16" until the horizontal row opposite 8" is reached, 19 $\frac{1}{4}$ is found, which shows that the jack rafter must be cut 19 $\frac{1}{4}$ inches shorter than the main rafter and that each succeeding jack rafter must be cut 19 $\frac{1}{4}$ inches shorter than the preceding jack rafter. 70

It is obvious that the width of $\frac{1}{2}$ of the building is given in tables 5 and 6 in whole numbers, and it is to be understood that I 75 may construct my table using whole numbers and fractions if so desired.

Having fully described my invention, I claim:

In a device of the character described, a 80 triangle square, a blade pivotally connected to the same near its apex, the apex portion of said triangle square being provided with a plurality of diverging lines, which intersect at a common point, the inner edge of 85 said blade being disposed to coincide with a selected one of said lines, so that said blade may be adjusted to a desired position with relation to said triangle square, the arms of 90 said triangle square being connected by a section of material, said section of material being provided with a table, comprising horizontal rows of figures to indicate, one 95 the given lengths of run, and the others the resultant lengths of rafters to be cut, a vertical row of figures to indicate the rise per foot of the rafters, and said diverging lines being numbered to correspond to the numbers in the said vertical row.

In testimony whereof I affix my signature 100 in presence of two witnesses.

TERRILL WILLIAM McCORMICK.
